COMPOUND HYDRAULIC BRAKE
COMPRESSOR

Martin V. Groves, New York, N. Y., assignor of
one-half to Arthur Wilde and Arthur Hull-
Ryde, Bayside, N. Y.

Application November 20, 1940, Serial No. 366,333

14 Claims. (Cl. 60—54.6)

This invention relates to new and useful improvements in a compound hydraulic compressor especially useful in the actuation of hydraulic brake, or the like, systems. In some respects the invention is in the nature of an improvement over my prior United States Patent No. 2,179,241, issued November 7, 1939. Certain features of the present invention, disclosed but not claimed herein, form a part of my copending application Serial Number 463,165, filed October 24, 1942, for "Compound hydraulic compressors."

Devices of this sort comprise a large piston in a main cylinder and a relatively smaller piston in an auxiliary cylinder, suitably supplied with operating fluid. The pistons are simultaneously moved forward to quickly displace fluid by the large piston in a relatively large volume until a predetermined pressure is built up in the hydraulic system to be actuated, whereupon the smaller piston is released for continued movement relative to the large piston and displaces fluid into said large cylinder where the hydraulic advantage due to the difference in said cylinder sizes exerts a relatively high pressure on said system.

An object of the present invention is to provide a relatively simple, durable and dependable device of the character described.

Another object is to provide a device which is capable of effecting a smooth carry-over from low pressure to high pressure, and one in which such carry-over may be provided at a predetermined pressure.

Another object is to provide a device in which the actuating fluid is readily and quickly vented so as to permit rapid restoration of the parts to inactive position.

Further objects and advantages of the invention will more fully appear from the following description taken in connection with the accompanying drawings which show, by way of example the present preferred embodiment of the invention.

The invention consists of the novel feature, arrangement, and combination of parts embodied by way of example in the mechanism hereinafter described as illustrating the present preferred forms of the invention, and the invention will be more particularly pointed out in the appended claims.

Referring to the drawings, in which the same reference characters indicate the same parts in the various views:

Fig. 1 is a vertical longitudinal sectional view

of a compound hydraulic compressor constructed in accordance with this invention.

Fig. 2 is a vertical sectional view similar to Fig. 1 but illustrating the parts with the main and auxiliary pistons moved forward as a unit.

Fig. 3 is another sectional view similar to Fig. 2 but illustrating the auxiliary piston moved forwards relative to the main piston.

Fig. 4 is a vertical sectional view taken on the line 4—4 of Fig. 1.

Fig. 5 is an enlarged detailed view of a portion of Fig. 1.

Fig. 6 is a vertical longitudinal sectional view of a compound hydraulic compressor constructed in accordance with another embodiment of this invention.

Fig. 7 is a vertical sectional view similar to Fig. 6 but illustrating the parts with the main and auxiliary pistons moved forwards as a unit.

Fig. 8 is another sectional view similar to Fig. 6 but illustrating the auxiliary piston moved forwards relative to the main piston.

Fig. 9 is an enlarged detailed view of a portion of Fig. 6.

25 The compound hydraulic compressor, according to this invention, includes a hollow body 10 for holding a hydraulic fluid 11 and having a cylinder 12 provided with a large bore 12^a in its front end and a small bore 12^b in its rear end and with a closed end 10^a, which end is provided with an opening 13 for connection with a pipe line for supplying the hydraulic fluid to the hydraulic brakes. A main piston 15 is slidably mounted in the cylinder 12 and is formed with a small bore 16 in its rear end. An auxiliary small piston 17 is slidably mounted in the bore 16.

30 A means is provided for urging the small piston 17 forwards for applying the brakes and this means includes a piston rod 18 connected with the rear of the piston 17 and extending from the rear end of the body 10 and adapted to be connected with a foot pedal, or linkage, or other mechanism by which the piston rod 18 may be manually moved forwards and rearwards.

45 Hydraulic fluid means is provided for normally connecting the pistons 16 and 17 together as a unit and this means is controlled with a pressure loaded valve 19 actuated by pressure of the hydraulic fluid in the bore 16 of the main piston 15 and controlling passages 20 arranged to connect the bore 16 with the rear end of the main piston 15 for connecting or disconnecting the fluid in the bore 16 with the fluid to the rear of the main piston 15 to connect or disconnect these pistons.

More specifically the passages 20 connect with a compartment 20^a in the rear end of the small piston 17. This compartment 20^a is connected by passages 20^b through the wall of the small piston 17 to the compartment 20^c which is located to the rear of the cylinder 12 behind the main piston 15. The valve 19 is slidably mounted in a cylindrical opening of an outer one way valve 21. A rubber cup 19^a is engaged upon the head of valve 19 and in face contact therewith has a smaller piston 19^b also arranged adjacent the head of the valve 19. An expansion spring 22 is located within the body of the outer valve 21 and acts against the small piston for normally urging this latter valve closed. It is illustrated in its closed position in Figs. 1 and 2.

In its closed position the inner end of the valve 19 projects across the inner end of the passages 20 closing the same against the passage of fluid therethrough. When the pressure of the hydraulic fluid to the front of the valve 19 opens the valve 19 it will be moved rearwards compressing the spring 22 and causing the fluid to the rear of the valve to pass between the edge of the rubber cup 19^a and the valve body 21 to engage behind the enlarged head of the valve 19 and the adjacent end of the valve body 21 for locking the valve 19 in its open position to permit the hydraulic fluid to pass through passages 20 and into the compartment 20^a.

However, the rubber cup 19^a is formed with an opening 19^{aa} and the piston 19^b is formed with an opening 19^{bb} in an aligned position with the opening 19^{aa} through which the entrapped fluid is adapted to pass for freeing the rubber cup 19^a and piston 19^b to permit the spring 22 to again expand and urge these members into position upon the end of the valve 19. From a careful inspection of Fig. 5 it will be noted that the metallic piston 19^b is of smaller diameter than the bore of the valve body 21, therefore when the valve 19 moves rearwards to expose the passages 20 the hydraulic fluid contained within the valve body may easily discharge around the peripheral edge of the rubber cup 19^a by flexing the same out of engagement with relation to its adjacent wall. This rubber cup is formed with a flange which is directed towards the valve 19 and acts to lock the entrapped fluid and prevent the same from again discharging around this said peripheral edge.

When the brake is released the pressure in front of valve 19 and in the passage 20^a is released. The pressure of the fluid in back of the valve 19 in the space between the cup 19^a and the wall of the valve body 21 will then separate the cup 19^a from its seat on the rear flange of the valve 19, which will allow the trapped fluid to pass through the opening 19^{aa} in the cup 19^a and the opening 19^{bb} in the piston 19^b to the passage 20^a, thus allowing the spring 22 to expand and return the valve 19 to its closed position.

The valve 21 has a head 21^a cooperative with an adjacent seat formed internally in the piston 17. The valve 21 is urged upon its seat by an expansion spring 23 which is disposed within the bore 16 and acts between the front end of the bore and the valve head 21^a.

The piston rod 18 is slidably mounted in the rear end of the cylinder 12. Packing material 25 surrounds the piston rod 18 and operates in conjunction with the adjacent wall of the cylinder for preventing leakage of the hydraulic fluid from the body 10. Packing material 26 is mounted upon the front end of the small piston 17 and

is cooperative with the wall of the bore 16 for preventing leakage of hydraulic fluid from the front of the bore to the rear of the bore.

The cylinder 12 is provided with a passage 27 through which the hydraulic fluid 11 may enter a compartment 28 located between a front flange 19 formed on the main piston 15, and a rear flange 30 formed on a rear area of the main piston 15. Another passage 32 connects the compartment 29 with a compartment 33 at the rear of the main piston 15 directly behind a flange 34 formed on the front of the small piston 17.

Another passage 35 extends through the wall of the cylinder 12 and allows the passage of hydraulic fluid 11 to the front of the cylinder 12 when the main piston 15 is in its rear position as illustrated in Fig. 1. However, when the main piston moves forwards the passage 35 is immediately closed. The front portion of the main piston 15 is provided with a reduced tapered end 36 upon which an annular packing cup or member 37 is mounted. A spring 38 urges this packing member 37 against the flange 29.

A check valve 40 is mounted across the discharge opening 13 at the front of the cylinder 12. This check valve 40 has a skirt portion 40^a and a base portion 40^b. The base portion 40^b is supported upon a retainer cap 41. This retainer cap 41 has passages 42 in its side walls which are controlled by the skirt portion 40^a of the valve. The retainer cap 41 is rested against a rubber washer 43 mounted across the front end of the cylinder 12. A metal bushing 44 is mounted around the metal cap 41. The spring 38 engages about and supports the retainer bushing and urges the retainer bushing forwards so as to clamp the metal cap 41 in position and so support the check valve.

The front wall 10^a of the body 10 is arranged with a removable cap 10^b which is threadedly mounted upon the cylinder 12. The piston rod 18 is threadedly engaged into the rear end of the small piston 17. A removable plug 46 is mounted upon the top of the body 10 and may be removed when additional hydraulic fluid must be added to the brake system. This plug 46 is provided with vent passages 47.

Means is provided for cutting off the chamber 20^c from the chamber 33 to prevent fluid from passing from the chamber 20^c into the compartment 33, during the time that the piston 17 is moving forward relative to the piston 15. This means includes a valve 50 controlling the passage of hydraulic fluid between the chambers 33 and 20^c. More specifically, the valve 50 is slidably mounted around the auxiliary piston 17 and is cooperative with a valve seat 51 formed upon a skirt portion 52 on the rear of the main piston 15. This skirt portion 52 has several passages 53 through its side walls. An annular member 54 is removably supported upon the rear of the skirt portion 52. A plurality of expansion springs 55 act between this annular member 54 and the valve 50 for urging the valve upon its seat 51. The auxiliary piston 17 is formed with a flange portion 56 normally engaging the valve 50 and holding the valve open so that there is a free passage of hydraulic fluid between the compartments 33 and 20^c. However, when the auxiliary piston 17 moves forwards relative to the main piston 15 the flange 56 disengages from the valve 50 which then automatically closes.

A packing ring 63 is mounted on the piston 15 to the rear of the flange 30 and engages the wall of the cylinder 12^b.

The operation of the device is as follows:

With the parts as illustrated in Fig. 1 the brake is off. To apply the brake, the piston rod 18 is moved forwards. Since there is hydraulic fluid entrapped in the bore 16 which binds the main piston 15 with the auxiliary piston 17 as a unit, the main piston 15 will move forwards an amount identical to the movement of the piston rod 18. Because of the relative large diameter of the main piston 15 moving forwards in the cylinder 12, a relatively large amount of hydraulic fluid within the cylinder 12 will be displaced through the opening 13 to fill up the hydraulic line to the brakes and move the brake shoes against the brake drum. When this position is reached the parts will be in the condition illustrated in Fig. 2. Further forward pressure on the piston rod 18 will cause an increase in the pressure of the hydraulic fluid within the bore 16.

An increase in the pressure in the bore 16 will be transmitted to open the valve 19. The pressure will now be communicated through the passages 20 and 20^b to the compartment 20^c, which will then act against the rear of the main piston 15 for urging the main piston forwards. When the valve 19 opens the entrapped fluid in the bore 16 starts escaping which then permits the auxiliary piston 17 to move forwards relative to the main piston 15. Immediately the flange 56 moves forwards off the valve 50 which then closes. The hydraulic fluid which now passes from the bore 16 through the passages 20 and 20^b to the compartment 20^c and will now act to force the main piston 15 forwards.

Because of the relative small diameter of the auxiliary piston 17 the hydraulic pressure to the rear of the main piston 15 will be materially increased even though the force which moves the piston rod 18 forwards remains constant. Thus there is now a hydraulic mechanical advantage present. The increased hydraulic pressure will serve to apply the hydraulic brakes with relatively great force. Soon the parts reach the position shown in Fig. 3 and now the hydraulic brake is fully applied.

The check valve 40 permitted the hydraulic fluid within the cylinder 12 to the front of the main piston 15 to pass through the openings 42 to the discharge through the opening 13. The spring 38 became compressed during the forward motion of the main piston 15. The pressure of the spring 38 maintains the metal cap in position and prevents the metal cap 40 from lifting off from the rubber washer 43 thus preventing any escape of the hydraulic fluid from the brake system back into the cylinder 12.

The brake is released in the following manner: The rod 18 is moved rearwards. The hydraulic fluid will immediately be sucked into the bore 16. The valve 21 opens for this purpose. The hydraulic fluid then passes from the compartment 20^c through the passages 20^b and past the valve head 21^a. This releases the extra pressure behind the main piston 15. When the auxiliary piston 17 reaches a position in which the flange 56 opens the valve 50, there will now be a passage from the compartment 20^c to the compartment 33. The hydraulic fluid in the compartment 20^c is therefore no longer entrapped and now the main piston 15 may move rearwards. The check valve cap 41 lifts from its seat due to suction and the hydraulic fluid re-enters thru passage 13 from the brake system, flowing into the front of the cylinder 12. This continues until the

pistons reach the positions shown in Fig. 1. The brakes are now completely released.

It should be noted that the check valve 40 is protected by the retainer bushing 44 which also retains the front of the spring 38. The spring holds the packing 37 in position. In this position the packing 37 closes several bleed holes 29^a formed in the flange 29. The retainer bushing 44 protects the check valve 40 when the piston 15 is urged forwards during a bleeding operation of the hydraulic brakes. The packing 37 is in the form of a retainer cup for the spring 38. This packing 37 is placed on the tapered end 36 of the piston 15 so that during the suction stroke of the bleeding operation the suction will pull it off its tapered seat, allowing the hydraulic fluid to pass through the bleed vents 29^a and pass between the wall of the piston and the packing 37 into the brake system.

In Figs. 6 to 9, inclusive, another form of the invention has been disclosed which has certain general features in common with prior mentioned patent. In this form of the invention the passage 13 is provided with the check valve 40 of a construction similar to that previously described and which is held in position by the retainer spring 38'. This retainer spring also holds the packing cap 37' in position on the tapered front end 36' of the auxiliary piston. The high pressure valve is located upon the front of the main piston 15. With this arrangement the high pressure fluid will be discharged to the front of the main piston 15 into the brake system.

The high pressure valve 19 controls passages 20^x discharging to the front of the main piston 15. These passages 20^x are located in the stem portion 21^x of the valve 21'. The high pressure valve 19 is similar to that previously described and is urged into a closed position by the spring 22' mounted between it and a washer 60 extended across the front end of the stem 21^x.

The valve 21' is urged closed by a small spring 23^x acting between the valve cap 61. This cap 61 is slidable in the bore 16. The cap 61 is urged forwards by a spring 23^y acting between the cap and the front end of the auxiliary piston 17'. A valve 50' is mounted in the rear end of the main piston 15 and controls the passage of hydraulic fluid from the compartment 33 to the compartment 20^c. Packing material 63 is mounted upon the rear portion of the main piston 15.

In other respects this form of the invention is similar to the previous form and like parts are identified by like reference numerals.

The operation of this form of the invention may be understood by first noting the position of the parts in Fig. 6 in which the brake is off. When the connecting rod 18 is moved forwards the pistons 15 and 17' will move frontwards as a unit. They are rigidly connected together because of the hydraulic fluid entrapped in the bore 16. When the parts reach the position shown in Fig. 7, the main piston 15 will meet resistance and the auxiliary piston 17 will still travel forwards. This increases the pressure in the bore 16 so that the high pressure valve 19 opens and is locked open by the passage of hydraulic fluid and the peripheral edge of the rubber cup 19^a. The hydraulic fluid from the bore 16 may now pass through the passages 20^x to the front of the main piston 15.

At the instant that the auxiliary piston 17 starts moving forwards relative to the main piston 15, the flange 56 releases the valve 50' which

closes (Fig. 8). This entraps hydraulic fluid in the compartment 28^c to the rear of the main piston 15. Consequently it cannot move rearwards at this time. It is noted in this connection that the fluid displaced in the small cylinder 16 ahead of the forward piston ring 26 is of relatively great volume compared to the minor volume displaced by the rear piston ring 25 from the annular space surrounding the piston 17' within the chamber 12^b. Accordingly, in this preferred arrangement the large piston 15 is not held absolutely stationary by the fluid trapped in the chamber 28^c by the valve 50' but is urged slightly forward by the relatively small displacement of fluid from the chamber 12^b ahead of the piston ring 25 (Fig. 8). This provides a factor of safety against the rearward motion of the piston 15 during the displacement of fluid from the small cylinder 16 ahead of the small piston ring 26, and assures a more smooth carry-over from the low pressure to the high pressure exerted on the brake line. Thus the hydraulic fluid from the bore 16 can be forced into the brake system. The parts are in the position shown in Fig. 8 when the brake is fully applied.

When the brake is released the connecting rod 18 is moved rearwards which moves the auxiliary piston 17' rearwards. When the pressure of the fluid against the valve 19 drops it causes the high pressure valve 19 to close, but now the valve 21' opens. The fluid from the front of the main piston 15 may now pass the valve 21' and enter the bore 16. This continues until the flange 56 reopens the valve 50'. Then the auxiliary piston 17' moves rearwards simultaneously with rearward motion of the main piston until the parts reach the position shown in Fig. 5. The brake is now off.

During the bleeding operation of the brake system the main piston 15 may be moved forwards until the valve stem 21^x strikes the metal cap of the check valve 40. This forces the valve 21' open, bleeding the bore 16. In other respects the operation is identical.

While I have illustrated and described the preferred embodiments of my invention, it is understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A compound hydraulic brake compressor, comprising a cylinder formed with a closed front end which is provided with an opening for connection with the fluid line of hydraulic brakes, a main piston slidably mounted in said cylinder and having a small bore providing an auxiliary cylinder, an auxiliary small piston slidably mounted in said bore, means for urging said small piston forwards for applying the brakes, hydraulic fluid means for normally rigidly connecting said pistons together as a unit and controlled with a pressure loaded valve actuated by pressure of the hydraulic fluid and controlling a passage extending from said auxiliary cylinder to the rear of said main cylinder, for connecting the fluid in said auxiliary cylinder with the fluid in the rear of said main cylinder to disconnect the pistons, a one way valve controlling a passage through which fluid from the rear of said main cylinder may enter said auxiliary cylinder upon rearward motion of said auxiliary piston,

means for normally urging said main piston rearwards, and means for normally urging said auxiliary piston rearwards, said pressure loaded valve opening said passage upon a predetermined pressure and thereby permitting movement of the auxiliary piston relative to the main piston to discharge fluid to the rear of the main cylinder for moving the main piston forward.

2. A compound hydraulic brake compressor, comprising a cylinder formed with a closed front end which is provided with an opening for connection with the fluid line of hydraulic brakes, a main piston slidably mounted in said cylinder and having a small bore providing an auxiliary cylinder, an auxiliary small piston slidably mounted in said bore, means for urging said small piston forwards for applying the brakes, hydraulic fluid means for normally rigidly connecting said pistons together as a unit and controlled with a pressure loaded valve actuated by pressure of the hydraulic fluid and controlling a passage extending from said bore to the rear end of said main piston, said pressure loaded valve opening said passage upon a predetermined pressure and thereby permitting movement of the auxiliary piston relative to the main piston to discharge fluid to the rear of the main cylinder for moving the main piston forward, a one way valve controlling a passage through which fluid from the rear of said main cylinder may enter said bore upon rearward motion of said auxiliary piston, means for normally urging said main piston rearwards, and means for normally urging said auxiliary piston rearwards, said pressure loaded valve being disposed within said one way valve.

3. A compound hydraulic brake compressor, comprising a body for holding a hydraulic fluid and having a cylinder formed with a large front bore and a small rear bore and with a closed front end and which is provided with an opening for connection with the fluid line of hydraulic brakes, a main piston slidably mounted in said cylinder and having a small bore in its rear end, an auxiliary small piston slidably mounted in said bore, means for urging said small piston forwards for applying the brakes, hydraulic fluid means for normally rigidly connecting said pistons together as a unit and controlled with a pressure loaded valve actuated by pressure of the hydraulic fluid and controlling a passage extending from said bore to the rear end of said main piston, for connecting the fluid in the bore with the fluid at the rear of the main piston to disconnect the pistons, a one way valve controlling a passage through which fluid from the rear of said cylinder may enter said bore upon rearward motion of said auxiliary piston, means for normally urging said main piston rearwards, means for normally urging said auxiliary piston rearwards, and means for cutting off the fluid to the rear of said main piston from the fluid in said body during the time the auxiliary piston is moving forward relative to said main piston, said pressure loaded valve being disposed within said one way valve, said one way valve being disposed in the rear portion of said auxiliary small piston.

4. A compound hydraulic brake compressor, comprising a body for holding a hydraulic fluid and having a cylinder formed with a large front bore and with a small rear bore and with a closed front end and which is provided with an opening for connection with the fluid line of hydraulic brakes, a main piston slidably mounted in said

- cylinder and having a small bore in its rear end, an auxiliary small piston slidably mounted in said bore means for urging said small piston forwards for applying the brakes, hydraulic fluid means for normally rigidly connecting said pistons together as a unit and controlled with a pressure loaded valve actuated by pressure of the hydraulic fluid and controlling a passage extending from said bore to the rear end of said main piston, for connecting the fluid in the bore with the fluid at the rear of the main piston to disconnect the pistons, a one way valve controlling a passage through which fluid from the rear of said cylinder may enter said bore upon rearward motion of said auxiliary piston, means for normally urging said main piston rearwards, means for normally urging said auxiliary piston rearwards, and means for cutting off the fluid to the rear of said main piston from the fluid in said body during the time the auxiliary piston is moving forward relative to said main piston, said pressure loaded valve being disposed within said one way valve, said one way valve being disposed in the rear portion of said auxiliary small piston, the passages controlled by said pressure loaded valve being disposed in the stem of said one way valve.
5. A compound hydraulic brake compressor, comprising a body for holding a hydraulic fluid and having a cylinder formed therein with a closed front end which is provided with an opening for connection with the fluid line of hydraulic brakes, a main piston slidably mounted in said cylinder and having a small bore providing an auxiliary cylinder, an auxiliary small piston slidably mounted in said bore, means for urging said small piston forwards for applying the brakes, hydraulic fluid means for normally rigidly connecting said pistons together as a unit and controlled with a pressure loaded valve actuated by pressure of the hydraulic fluid and controlling a passage extending from said bore to said main cylinder to the rear of said main piston, for connecting the fluid in the bore with the fluid at the rear of the main piston to disconnect the pistons, a one way valve controlling a passage through which fluid from said main cylinder may enter said bore upon rearward motion of said auxiliary piston, means for normally urging said main piston rearwards, and means for normally urging said auxiliary piston rearwards, said pressure loaded valve opening said passage upon a predetermined pressure and thereby permitting movement of the auxiliary piston relative to the main piston to discharge fluid to the rear of the main cylinder for moving the main piston forward, whereby said main piston transmits relatively high pressure to said fluid line through said opening in the front end of said main cylinder.
6. A compound hydraulic brake compressor, comprising a cylinder formed with a closed front end which is provided with an opening for connection with the fluid line of hydraulic brakes, a main piston slidably mounted in said cylinder and having a small bore in its rear end providing an auxiliary cylinder, an auxiliary small piston slidably mounted in said bore, means for urging said small piston forwards for applying the brakes, hydraulic fluid means for normally rigidly connecting said pistons together as a unit and controlled with a pressure loaded valve actuated by pressure of the hydraulic fluid and controlling a passage extending from said auxiliary cylinder to the front end of said main piston for connect-
- 10 5 ing the fluid in the auxiliary cylinder with the fluid at the front of the main piston to disconnect the pistons, said first cylinder and piston also providing a chamber adjacent the rear end of said cylinder into which fluid is adapted to pass during forward movement of the piston, and valve means controlling the fluid passing into said rear chamber for holding said main piston against rearward motion.
- 15 10 5 7. A compound hydraulic brake compressor, comprising a cylinder formed with a closed front end which is provided with an opening for connection with the fluid line of hydraulic brakes, a main piston slidably mounted in said cylinder and having a small bore providing an auxiliary cylinder, an auxiliary small piston slidably mounted in said bore, means for urging said small piston forwards for applying the brakes, hydraulic fluid means for normally rigidly connecting said pistons together as a unit and controlled with a pressure loaded valve actuated by pressure of the hydraulic fluid in the front end of said cylinder and controlling a passage extending from said bore to the front end of said main piston for connecting the fluid in the bore with the fluid at the front of the main piston to disconnect the pistons, said pressure loaded valve opening said passage upon a predetermined pressure and thereby permitting movement of said auxiliary piston relative to said main piston to discharge fluid to the front of said main cylinder, means for trapping holding fluid behind said main piston to prevent its rearward movement during said discharge of fluid to the front of said main cylinder, whereby resultant pressure is exerted through said fluid line opening, a one way valve controlling a passage through which fluid from the front of said cylinder may enter said bore upon rearward motion of said auxiliary piston, means for normally urging said main piston rearwards, and means for normally urging said auxiliary piston rearwards, said high pressure valve being disposed coaxially through said one way valve.
- 20 15 10 5 8. A compound hydraulic brake compressor, comprising a body for holding a hydraulic fluid and having a cylinder formed with a large front bore and a small rear bore and with a closed front end which is provided with an opening for connection with the fluid line of hydraulic brakes, a main piston slidably mounted in said cylinder and having a small bore in its rear end, an auxiliary small piston slidably mounted in said bore, means for urging said small piston forwards for applying the brakes, hydraulic fluid means for normally rigidly connecting said pistons together as a unit and controlled with a pressure loaded valve actuated by pressure of the hydraulic fluid in the front end of said cylinder and controlling a passage extending from said bore to the front end of said main piston for connecting the fluid in the bore with the fluid at the front of the main piston to disconnect the pistons, said pressure loaded valve opening said passage upon a predetermined pressure and thereby permitting movement of said auxiliary piston relative to said main piston to discharge fluid to the front of said main cylinder, means for trapping holding fluid behind said main piston to prevent its rearward movement during said discharge of fluid to the front of said main cylinder, whereby resultant pressure is exerted through said fluid line opening, a one way valve controlling a passage through which fluid from the front of said cylinder may enter said bore upon rearward mo-

tion of said auxiliary piston, means for normally urging said main piston rearwards, and means for normally urging said auxiliary piston rearwards, said high pressure valve being disposed coaxially through said one way valve.

9. In a hydraulic brake compressor, the combination of a main cylinder, a double-ended piston positioned therein and having a bore providing an auxiliary cylinder, front and rear main cylinder chambers being provided on respectively opposite ends of said double-ended piston, said front chamber being provided with an opening for connection with the fluid line of hydraulic brakes, the other of said chambers being in communication with a supply of fluid, an auxiliary piston in said auxiliary cylinder, means to impart forward motion to said auxiliary piston, valve means actuated by the forward movement of said auxiliary piston to close said other chamber from communication with said fluid supply, and valve means constructed and arranged to hydraulically lock said pistons together during the first part of forward movement of said auxiliary piston and during the second part of forward movement upon a predetermined pressure being attained to release said small piston for relative motion with respect to said large piston and to transmit fluid from said auxiliary cylinder to said main rear chamber for imparting forward motion to said main piston, whereby the resultant high pressure is transmitted to said fluid line through said first mentioned chamber.

10. In a hydraulic brake compressor, the combination of a large cylinder, a piston in hydraulic sealing engagement therein and having a bore providing a small cylinder, a small piston in said small cylinder and extending rearwardly of said large piston, said large piston having a fluid seal adjacent its front end providing a hydraulic chamber between it and front end of said large cylinder and a fluid seal adjacent its rear end providing a hydraulic chamber between it and the rear end of said large cylinder exteriorly of said small piston, said large piston also having a portion intermediate said front and rear seals between which and an adjacent part of said main cylinder a first compartment is provided, a portion of said small piston and the corresponding portion of its cylinder providing therebetween a second compartment, said first and second compartments and rear chamber being in communication, first valve means constructed and arranged to close said rear chamber from said second compartment upon forward movement of said small piston, second valve means interposed between said small cylinder and one of said large cylinder chambers constructed and arranged to hydraulically lock said large and small pistons for forward motion upon forward movement of said small piston and upon predetermined pressure being reached in said chamber to place said high pressure cylinder in fluid communication with one of said large cylinder chambers, whereby relatively high hydraulic pressure is imposed on both ends of said large piston and the resulting hydraulic pressure is transmitted through the front chamber of said large cylinder to the brake line.

11. In a compound hydraulic brake compressor, the combination of a low pressure cylinder, a low pressure piston within said cylinder and provided with an axial bore serving as a high pressure cylinder, a high pressure piston positioned within said bore and extending rearwardly of said low pressure piston, said low

pressure cylinder and low pressure piston and high pressure piston being constructed and arranged so as to provide a chamber rearwardly of said low pressure piston and surrounding said

5 high pressure piston, said chamber being in communication with a passage provided between said pistons and said passage being in communication with a fluid supply, means for urging said small piston forward to actuate said compressor, 10 and pressure loaded valve means interposed between said low pressure cylinder and said high pressure cylinder so constructed and arranged that said pistons are hydraulically locked together until a predetermined brake line pressure is attained and are then released for relative movement, and a second valve means interposed between said pistons for closing said passage to said chamber and constructed and arranged to be operable to close said passage upon the forward movement of said high pressure piston, said parts being so constructed and arranged that upon the unloading of said first valve and the actuation of said second valve relatively high pressure is induced in said low pressure cylinder 25 by the forward movement of said high pressure piston, said low pressure cylinder being provided with an outlet positioned in front of said low pressure piston for transmitting said high pressure to said brake.

30 12. In a hydraulic brake compressor, the combination of a main cylinder, a double-ended piston positioned therein and having a bore providing an auxiliary cylinder, front and rear main cylinder chambers being provided on respectively opposite ends of said double-ended piston, said front chamber being provided with an opening for connection with the fluid line of hydraulic brakes, the other of said chambers being in communication with a supply of fluid, an auxiliary piston in said auxiliary cylinder, means to impart forward motion to said auxiliary piston, valve means actuated by the forward movement of said auxiliary piston to close said other chamber from communication with said fluid supply, and valve means constructed and arranged to hydraulically lock said pistons together during the first part of forward movement of said auxiliary piston and during the second part of forward movement upon a predetermined pressure being attained to release said small piston for relative motion with respect to said large piston and to transmit fluid from said auxiliary cylinder to one of said chambers, whereby a resultant relatively high pressure is 45 created in both of said chambers on opposite ends of said piston, said rear chamber being provided with an intercommunicating rearwardly extending cylindrical bore of smaller diameter than that of said main cylinder, and a supplemental piston disposed therein and connected for movement with said auxiliary piston, the displacement of said supplemental piston being substantially less than that of said auxiliary piston, 50 whereby an added increment of pressure is inserted against the rear of said main piston during the second part of the forward movement of said auxiliary piston.

13. A fluid pressure producing device comprising a cylinder, a piston movable therein and 55 dividing the cylinder into two chambers, one of said chambers having a discharge port and the other of said chambers adapted to draw fluid therein during movement of the piston, means controlling the fluid drawn into said chamber, said piston having a small chamber communicat-

ing with the chamber having the discharge port, means for control of the communication, and means for subjecting the fluid in the small chamber to pressure.

14. A fluid pressure producing device comprising a cylinder, a piston movable therein and dividing the cylinder into two chambers, one of said chambers having a discharge port and the other of said chamber adapted to draw fluid

therein during movement of the piston, means controlling the fluid drawn into said chamber, said piston having a small chamber communicating with one of the chambers provided in said cylinder, means for control of the communication, and means for subjecting the fluid in the small chamber to pressure.
